[57] CLAIM

The ornamental design for a beer keg tapping kit, as
shown and described.

DESCRIPTION

FIG. 1 is a front perspective view of a beer keg tapping
kit showing my new design in an open condition;
FIG. 2 is a top plan view in a closed condition, a portion
thereof broken away for purposes of illustration;
FIG. 3 is a rear elevational view thereof in a closed
condition;
FIG. 4 is a front elevational view thereof; and
FIG. 5 is a bottom plan view thereof.
